PENCIL-SHARPENING MACHINE

Gerald Dahle, Coburg, Germany, assignor to
Wilhelm Dahle, Coburg, Germany

Application January 21, 1953, Serial No. 332,380

10 Claims. (Cl. 120—96)

1 The present invention relates to a pencil-sharpening machine, the milling or cutting assembly or the casing thereof being supported at one side while the container or receptacle for cuttings is arranged underneath the aforesaid cutting assembly.

In these pencil sharpening devices it has hitherto been the habit to support the cutting assembly transversely to its rotation axis from underneath, securing the support near the point at which the crank handle acts upon said cutting assembly.

The advantage of an arrangement of this sort is that it allows a comparatively large choice of space beneath the cutting assembly. There is 15 the disadvantage, however, that the cutting assembly rocks in the direction of its axis when actuated by the handle. This resulted in the support being highly stressed particularly at the point where it is connected with the cutting assembly so that it is necessary to make both the support and the place at which it is connected very strong. But even if these latter conditions are complied with the continual stressing between the cutting unit and its support soon causes this part of the machine to fail. The vibrations in this type of machine have also an adverse effect on the sharpening and the pencil point is frequently broken off.

The object of the invention is to produce a support for the cutting assembly which will be very economical as regards construction, the design of the said support being such that there will be plenty of room for collecting the cuttings. This is achieved according to the present invention through the cutting unit being supported at one side in a direction parallel to its axis of rotation. This method, in spite of the one-sided suspension of the cutting unit, gives a uniform distribution of the moments which occur on actuating the crank handle, causing them to be taken up in the longitudinal direction of the axis of rotation of the cutting unit.

The support according to the invention can be made in a number of different forms. It can, for example, according to one feature of the invention, be constructed in the form of a plate, the surface of this plate bounding the free space under the cutting unit in the direction of the axis of the cutting unit on one side. It may, however, consist of two strut members or the like located on the same side of the cutting unit and engaging at both ends of this unit. When the supporting means are in one place they preferably engage, according to a further feature of the invention,

2 the horizontally extending diameter of the cylindrical casing of the cutting unit in tangential manner. They may, however, extend outwardly in a curved manner.

5 According to a further feature of the invention, at least the supporting means and the base plate of the machine, preferably also however the casing of the cutting assembly, should consist of one piece.

10 In order that the particularly favourable shape of the space may be used, the receptacle or container for the cuttings extends at least at the free side beyond the diameter of the cutting unit and curves round to the casing of the unit.

It might also if desired extend through the recess provided in the support to the other side.

20 In another form according to the present invention the support extending along a plane forms an acute angle to the base and it is advantageous in such a case to make the external surfaces of the cutting container extend symmetrically thereto.

The accompanying drawings illustrate schematically a number of constructional examples 25 of the invention.

Figure 1 shows a perspective view of a pencil-sharpening machine according to the present invention.

Figure 2 is a cross-section on the line II—II of Figure 1.

Figure 3 is a section on the line III—III of Figure 1 with the pencil removed.

35 Figure 4 is a diagram of the support arrangement manufactured in one piece with the base plate and the holder for the cutting or milling unit.

Figure 5 shows an outwardly curved support for the cutting unit.

40 Figure 6 shows a support which extends at an acute angle to the bottom surface.

Figure 7 shows a support which consists of two struts.

The pencil-sharpening machine consists of a cylindrical casing 1 which takes the milling or cutting unit 2, this latter being set in movement by means of the hand crank element 3. At the front end of the cutting unit is disposed the gripping chuck 4 for the pencil which is to be sharpened. This chuck 4 is guided so that it is capable of displacement by means of a carrier 5 fixed to it at the side inside a holder arrangement 6 fixed to the casing 1. The holder 6 is provided with a slot 7 in which is guided a pin on the carrier member 5, this pin not being shown on the drawing; a spring 17 engages on this pin and is fixed

at its other end to the casing of the cutting unit in such a manner that it pulls the chuck 4 towards the cutting unit 2.

Connected with the casing 1 is the support part 8 engaging it in a direction parallel to the axis of rotation of the cutting unit and being bent at the bottom to form a base plate 9.

In the form of construction which is illustrated in Figure 7, this support is provided with a recess so that the actual support is formed by two struts 18 engaging at the same side with the casing of the cutter unit.

The base plate 9 is preferably let into a bottom support 10 and then fixed to it by means of screws, as illustrated in the cross-section of Figure 2. In the examples of Figures 1 to 4 the support 8 forms a plane which together with the cutter unit encloses and bounds the space beneath it at one side. In this space the container 11 is arranged, one of whose walls, the wall 12, runs parallel with the support 8 while the other wall 13 extends beyond the periphery of the cutter unit 2 or its casing 1 and curves over to the casing 1 at 14. An aperture 15 in the form of a longitudinal slot is provided in the bottom of the casing 1 for the shavings to pass into the container below. The large amount of space for accommodating cuttings can be seen from Figure 2. This space can be increased still more if the container 11 is made to project beyond the diameter of the cutter unit at its side which abuts against the support 8, as illustrated in Figure 5. It will be of course necessary, in order to be able to withdraw the container for the shavings laterally, for the top edge of the container part to be in a line lower than the bottom of the casing for the cutter unit.

As shown schematically in Figure 4 the casing surface 1, support 8 and the base plate 9 are manufactured in one piece. In this form of manufacture, the parts 8 and 9 are first made by pressing and then part 1 is formed by a bending operation.

According to a preferred construction, the base plate parts 16 are also bent at the same time or subsequently formed by pressing.

Instead of making the support member for the casing in the form a flat surface, it could also be in the form of a curved surface, as shown in Figure 5, that is, looking in the direction of the axis of rotation of the cutter unit, this support engaging the casing for the cutter unit. In this case as well, it may be manufactured in a single piece together with the base plate and the casing for the cutter unit.

The support 8 can also, as shown in Figure 6, extend downwardly in oblique direction so as to make an acute angle with the bottom surface. This is possible whether the support is formed as a flat surface or whether it forms a curved surface. A construction of this kind enables the support member and the external surface of the container for the cuttings to be made symmetrically while at the same time increasing the space for receiving the cuttings. A support of this kind can also be manufactured in one piece together with the base plate and the casing for the cutter unit.

I claim:

1. A pencil sharpening machine comprising the combination of a rotary cutter unit and means for supporting said unit in elevated position and

extending in a plane substantially parallel to the rotary axis of said cutter unit and at one side thereof, and a container below said cutter unit for receiving the pencil shavings, said container being at least partly enclosed and supported by said means.

2. A pencil sharpening machine as defined in claim 1 wherein the container is partly enclosed and supported by the supporting means so as to be removable toward the side opposite to said means.

3. A pencil sharpening machine as defined in claim 1 wherein said supporting means comprise a substantially horizontal base, a supporting member extending upwardly from said base and at one side of the rotary cutter unit, and an element extending from said member and substantially enclosing said cutter unit and forming a casing therefor.

20 4. A pencil sharpening machine as defined in claim 3, wherein said supporting member has an aperture therein for facilitating the removal of the container in the opposite direction therefrom.

25 5. A pencil sharpening machine as defined in claim 3, wherein the casing for supporting the cutter unit is of substantially cylindrical cross section.

30 6. A pencil sharpening machine as defined in claim 3, wherein the base, the supporting member and the casing for the cutter unit constitute a single integral element.

35 7. A pencil sharpening machine as defined in claim 3, wherein the base, the supporting member and the casing are formed by a single plate extending substantially parallel to the rotary axis of the cutter unit, said supporting member extending tangentially to said casing.

40 8. A pencil sharpening machine as defined in claim 1, wherein the container for receiving the pencil shavings and the supporting means have interengaging portions for normally retaining said container in a fixed position relative to said cutter unit.

45 9. A pencil sharpening machine comprising the combination of a rotary cutter unit, a single member for supporting said unit in an elevated position and comprising a plate extending parallel to the rotary axis of the cutter unit and being bent so as to form a substantially horizontal supporting base, a portion extending upwardly from said base and at one side thereof, and a curved portion substantially enveloping said cutter unit and supporting the same at one side of said upwardly extending portion and having an aperture at its lower side so as to allow the shavings to fall therethrough.

10. A pencil sharpening machine as defined in claim 9, wherein a container is provided for collecting the shavings, said supporting member at least partly enclosing and supporting said container below said cutter unit, and interengaging portions on said container and said supporting member for normally retaining the container in a fixed position relative to said cutter unit.
